UNITED STATES PATENT OFFICE.

OLOF MILLER, OF FARGO, NORTH DAKOTA.

STARCHING-MACHINE.

1,085,929.

Specification of Letters Patent. Patented Feb. 3, 1914.

Application filed April 17, 1913. Serial No. 761,826.

To all whom it may concern:

Be it known that I, OLOF MILLER, a citizen of the United States, residing at Fargo, in the county of Cass and State of North Dakota, have invented a new and useful Starching-Machine, of which the following is a specification.

This invention has reference to improvements in starching machines, and its object 10 is to provide a machine by which articles such as collars and the like may be readily starched in large numbers expeditiously and which machine requires the presence of but a single operator.

15 In accordance with the present invention there is provided a starch tank in which is normally lodged a suitable roller with feeding cords or belts in part encircling it and carried to a more distant idler roller, and 20 in addition to the main bands there are like cords or belts in approaching and receding relation to the first-named bands, and all so disposed that an operator standing at what may be termed the front of the machine may 25 place the articles to be starched upon the ingoing run of the feeding belt and take them from the outgoing run thereof, which outgoing run leads toward the front of the machine within easy reach of the operator.

30 The parts of the structure are so associated that cleansing is very readily performed, and, moreover, the starch is conducted into close relation to the articles to be starched and then surplus is removed so that on passing 35 the articles once or twice through the machine they are thoroughly starched ready for the subsequent operations.

The invention will be best understood from a consideration of the following detailed description, taken in connection with 40 the accompanying drawings forming a part of this specification, with the further understanding that while the drawings show a practical embodiment of the invention, the 45 latter is not confined to any strict conformity with the showing of the drawings but may be changed and modified so long as such changes and modifications mark no material departure from the salient features of 50 the invention.

In the drawings:—Figure 1 is a side elevation of the machine. Fig. 2 is a plan view thereof. Fig. 3 is a central longitudinal vertical section showing in dotted lines the position assumed by the parts when it is de-

sired to cleanse the machine. Fig. 4 is a plan view partly in section of pressing rollers designed to force the article to be starched firmly into engagement with the carrying roller.

60 Referring to the drawings, there is shown a tank 1 which may be of generally rectangular outline with one portion of the bottom sloping upwardly, as indicated at 2, until it reaches to or closely adjacent to the 65 top of the tank at a point which may be termed the front of the tank. This tank is supported upon a frame consisting of horizontal members or beams 3 and 4 and legs 5, all of which may be made of metal or wood, 70 as desired, but as shown in the drawings are made of angle or structural metal. The tank 2 is provided with a false bottom 6 at a distance above the main flat bottom of the tank to provide a chamber 7 having an inlet 75 8 and outlet 9 for steam or other heating fluid, while traversing the chamber 7 and opening into the tank through the false bottom 6 is a drain pipe 10 for the tank 2, and this drain pipe may be normally closed by 80 a plug 11 or in any other suitable manner, whereby starch may be readily drained from the tank 1 when desired.

Connected to each side beam 3 of the frame near the rear end thereof by a pivot 85 pin or bolt 12 is a bar 13, and secured to and rising from the pivoted end of the arm is a post 14, there being two such bars 13 and two such posts, and the posts are connected together by a cross piece 15. Each 90 post rises to an appropriate height and is there formed with a crown curve 16 and a downwardly extending leg 17, the end of which is made fast to the respective bar 13 at a distance forward of its pivot support, 95 the said bars 13 with the posts 14 constituting a pivoted frame extending lengthwise of the tank 1 when in operative position and carrying certain mechanism to be described, the whole structure being movable 100 about the pivots 12 until the bars 13 are upright and the posts 14 are approximately horizontal. The normal position of the bars 13 is horizontal and they are disposed so that one web extends outwardly from the 105 longitudinal center line of the machine and rests upon the upper edge of the corresponding side beam 3.

Each bar 13 at a point about midway of 110 the distance between the legs 5 of the sup-

porting frame carries a journal bearing 18 for the corresponding end of a shaft 19 carrying a drum 20 which may correspond in construction to drums as employed in starching machines of the general character to which the present invention relates. The drum 20 has a surface covering 21 of cloth, and in this respect may correspond to the practice in the art to which this invention relates. The drum 20 is of such length as to dip into the tank 1 to an appropriate depth for a purpose which will presently appear.

The depending web of each angle beam 13 is, when the parts are in operative position, within the tank 1, and fast to this web are bars 22 one near the rear end of the tank and the other near the junction of the false bottom 6 with the sloping front 2 of the tank, and these bars 22 at their lower ends carry rollers 23, 24, respectively, in traversing relation to and near the bottom of the tank 1 within the latter.

Each beam 3 near the front end carries a plate 25 with upturned ends 26 in spaced relation one to the other, and on this plate 25 between the ends 26 there is lodged a slidable journal block 27 having a pin 28 at one end traversing the respective upturned end 26 and another pin 29 at the other end traversing the other upturned end 26, while between the last named end 26 and the block 27 the pin 29 is surrounded by a spring 30 tending to maintain the block against the upturned end remote from the spring 30, this being the upturned end 26 at the front of the machine, but the spring 30 will yield to a superior force allowing the journal block 27 to slide along the plate 25 toward the rear of the machine. There are two blocks 27 one on each side of the machine, and these journal blocks receive journal ends 31 of a straining or tension roller 32 which roller is formed with a longitudinal series of circumferential grooves 33 in comparatively close relation one to the other and the spacing of the grooves may be equal throughout the series.

Between the crowns 16 of the posts 14 there extends a guide roller 34 suitably journaled to turn readily, and this roller has a longitudinal series of circumferential grooves 35 like the grooves 33 on the roller 32.

Offstanding from each leg 17 is an arm 36, this arm extending toward the front of the machine in an upward direction, although this particular arrangement is not mandatory, and the length of the arm is such that the front end thereof overhangs the tank 1 between the roller 21 and the straining or tension roller 32. There are two such arms 36 one on each side of the machine, and between these arms there extends a straining or tension roller 37 having journals 38 each mounted in a journal block

39 slidably carried on a plate 40 fast to the corresponding outer end of the respective arm 36. The block 39 has a pin 41 traversing an upturned end 42 of the plate 40 and on the opposite side of the block 39 there is a pin or rod 43 traversing an upturned end 44 remote from the upturned end 42 and between the end 44 and the block 39 the rod 43 is surrounded by a spring 45 tending to hold the block 39 against the upturned end 42.

At an intermediate point of each arm 36 is a bracket 46 and between the two brackets 46 there is journaled a roller 47 located about midway of the length of the two arms 36.

Extending between the legs 17 is a wiping roller 47^a smaller than the roller 20 and larger than the rollers 32, 34 and 37. This roller has terminal journals 48 each mounted in a slidable journal block 49 carried by a plate 50 on the respective leg 17, and this plate has upturned ends 51 through one of which a pin 52 on the corresponding end of the block 49 is passed, while a rod 53 projecting from the other side of the block 49 extends through the corresponding upturned end 51 of the plate 50 and is there threaded for the reception of nuts 53^a, 54, one of which, say the nut 54, may be a thumb nut, while between the nut 53^a and the block 49 the rod 52 is surrounded by a spring 55 tending to hold the block away from the nut 53^a.

Extending about the cloth covering 21 of the drum 20 and also about the roller 37 is a series of cords or belts 56 each traveling in a respective groove 57 in the roller 37, the said roller 37 having a longitudinal series of circumferential grooves 57 formed therein like the grooves 33 of the roller 32, and the grooves 35 of the roller 34. The drum 20 is also in part embraced by another series of cords or belts 58 each of which is endless and is carried about the roller 32 in a respective groove 33 and has one run extending beneath the roller 24 when the parts are in operative position, thence to the roller 23 and partially beneath and around the latter, thence carried upwardly to a groove of the roller 34, thence about the roller 47 and to and around the drum 20 at the side thereof remote from the roller 32, the belt finally returning to the roller 32. The drum or roller 47^a is provided with a cloth covering 59 like the cloth covering 21 of the drum 20.

Those bars 22 which carry the roller 24 each carry an arm 60 at one end, by means of a pivot pin 61 and this arm is curved on an arc struck from the shaft 19. The other end of each arm 60 is connected to a rod 62 extending through the flange portion of the crown 16 of the respective post 14 and above it surrounded by a spring 63 controlled by a thumb nut 63^a at the upper end of the rod. 130

Extending between the arms 60 and journaled therein are rollers 64 each having the surface corrugated and bearing against the corresponding portion of the drum 20 or the cloth covering on the drum within the tank 1 near the bottom thereof.

The shaft 19 is continued beyond one of the journal bearings 18 and there carries a worm gear wheel 65 which may in part run in a curved guard 66 underriding the wheel and supported by brackets 67 made fast to the legs 5 on the corresponding side of the machine. The guard 66 is formed with a casing 68 on its lower side carrying journal bearings 69 for a worm 70 meshing with the worm gear 65 and mounted on a shaft 71 having journal bearings 72 in the frame of the machine and provided with tight and loose pulleys 73, 74 for the application of power to the shaft 71 by a belt, although this driving structure may be considered as simply typical of any driving means whether by belt or pulley or directly connected electric motor or otherwise.

Let it be assumed that there is a suitable supply of starch within the tank 1 and the fluidity of this starch is maintained at any suitable degree by steam or other heating medium circulating in the compartment 7, and let it further be assumed that power is being applied to the shaft 71 in a direction to cause a rotation of the drum 20 in a clockwise direction as viewed in Figs. 1 and 3. If, now, collars or other like articles be placed upon the cords or belts 58 they will be carried thereby down into the starch, being gripped when reaching the roller 20 between the cords 58 and 56, these cords all traveling in the same direction when coincident, being impelled by the rotative movement of the drum 20. The articles to be starched are firmly held by the cords or belts 56 and 58 while underriding the drum 20 and there immersed in the starch, and when reaching the rollers 64 they are pressed with considerable force against the cloth surface 21 of the drum 20 and the starch is forced thoroughly into the material of the article. Ultimately these articles reach the roller 47^a which is in the nature of a pressure roller, being urged toward the roller 20 by the springs 55, the runs of the cords or belts 56 and 58 where traversing the cloth surfaces 21 and 59 sinking more or less thereinto, thus permitting the drums 20 and 47^a to approach sufficiently close to press out from the articles being starched any surplus starch which will fall down the steep rising side of the drum 20 to ultimately reach the supply of starch within the tank 1. As the respective runs of the cords 56 and 58 leave the drum 20, the cords 56 travel to the roller 37, while the cords 58 travel to the roller 47 and their direction of travel is diverted by the roller 47, from whence the cords 58 travel

to the roller 34, and finally downwardly therefrom to the roller 23, and from the latter about the roller 24 to the roller 32, from whence they again pass to the roller 20.

An operator standing at the front of the machine may place the articles to be starched upon the runs of the cords or belts 58 and may readily take the starched articles from the runs of the cords or belts 56 approaching the roller 37, so that but one operator is needed to attend to the machine and cause the starching of many hundred small articles such as collars and cuffs per hour.

What is claimed is:—

1. In a starching machine, a tank for starch, a drum mounted to dip into the tank below the starch level of the tank, tension rollers mounted one above the other and both on the same side of the drum, a wiping roller in operative relation to the drum at a high point thereon and on the rising side of the drum in the direction of its rotation, said drum being provided with means for imparting rotative movement thereto, cords or belts extending around the drum and the higher tension roller, other cords or belts extending around the lower tension roller and having one run partially embracing the main drum and extending between the wiping roller and the main drum, and guide rollers for the second named cords or belts.

2. In a starching machine, a tank for starch, a drum mounted to dip into the tank below the starch level of the tank, tension rollers mounted one above the other and both on the same side of the drum, a wiping roller in operative relation to the drum at a high point thereon and on the rising side of the drum in the direction of its rotation, said drum being provided with means for imparting rotative movement thereto, cords or belts extending around the drum and the higher tension roller, other cords or belts extending around the lower tension roller and having one run partially embracing the main drum and extending between the wiping roller and the main drum, and guide rollers for the second named cords or belts, the main drum having pressure rollers in engagement therewith at a low point within the tank.

3. In a starching machine, a tank for starch, a pivoted frame normally overriding the tank, a main drum carried by the frame in position to dip into the tank, a tension roller mounted on the frame at the end of the tank remote from the pivot of the frame, another tension roller on the same side of the main drum as the first-named tension roller and at a point above the main drum, a wiping roller above the main drum and on the side thereof remote from the tension rollers, cords or belts engaging the main drum and extending around the tension rollers, guide rollers for certain of the cords or belts, the tension rollers, guide rollers and

wiping roller all being mounted on the pivoted frame, and means for rotating the main drum.

4. In a starching machine, a tank for starch, a pivoted frame normally overriding the tank, a main drum carried by the frame in position to dip into the tank, a tension roller mounted on the frame at the end of the tank remote from the pivot of the frame, another tension roller on the same side of the main drum as the first-named tension roller and at a point above the main drum, a wiping roller above the main drum and on the side thereof remote from the tension rollers, cords or belts engaging the main drum and extending around the tension rollers, guide rollers for certain of the cords or belts, the tension rollers, guide rollers and wiping roller all being mounted on the pivoted frame, and means for rotating the main drum, the pivoted frame also having pressure rollers mounted thereon in position to underride the main drum in engagement therewith, and elastic connections between the mounting for the pressure rollers and the pivoted frame.

5. In a starching machine, a tank for starch, a frame of a size to enter the tank at the top thereof and pivoted at one end to move into and out of the tank about the pivot, said frame having a post on each side with a return leg and an outstanding arm extending toward the end of the tank remote from the pivot of the frame, a main drum mounted on the pivoted frame of a size to enter the tank below the starch level thereof, a tension roller mounted on the frame at the end thereof remote from the pivot, another tension roller mounted on the outstanding arms fast to the posts carried by the frame, a wiping roller carried by the legs extending from the posts in position to bear against the main drum, guide rollers carried by the frame below the drum and by the posts and arms above the main drum, and series of cords or belts, one series of cords extending around the first-named tension roller and the guide rollers and in part encircling the main drum, and another series of cords or belts extending around the main drum and the higher tension roller.

6. In a starching machine, a tank for starch, a frame of a size to enter the tank at the top thereof and pivoted at one end to move into and out of the tank about the pivot, said frame having a post on each side with a return leg and an outstanding arm extending toward the end of the tank remote from the pivot of the frame, a main drum mounted on the pivoted frame and of a size to enter the tank below the starch level thereof, a tension roller mounted on the frame at the end thereof remote from the pivot, another tension roller mounted on the

outstanding arms fast to the posts carried by the frame, a wiping roller carried by the legs extending from the posts in position to bear against the main drum, guide rollers carried by the frame below the drum and by the posts and arms above the main drum, and series of cords or belts, one series of cords extending around the first-named tension roller and the guide rollers and in part encircling the main drum, and another series of cords or belts extending around the main drum and the higher tension roller, said frame carrying pressure rollers in underriding relation to the main drum when in the starch tank and provided with an elastic connection to the posts rising from the pivoted frame.

7. A starching machine comprising a main frame, a starch tank mounted thereon, a pivoted frame having angle side members each with one web shaped to enter the tank and the other web to then rest on the main frame, a main drum journaled on the pivoted frame in position to enter the tank and having a driving gear exterior to the tank, driving means for the driving gear carried by the main frame and into and out of engagement with which driving means the gear of the main drum is movable with the pivoted frame, a tension roller mounted on the pivoted frame at the end thereof remote from the pivot of the said frame, posts rising from the pivoted frame adjacent the pivoted end, arms extending from the posts in overriding relation to the main drum to points adjacent the tension roller, another tension roller carried by the free ends of the arms, an elastically mounted wiping roller carried by the posts in position to engage the main drum at a high point thereof and on the rising side thereof when in operation, guide rollers carried by the pivoted frame both above and below the main drum, and cords or belts extending about the tension rollers, about the guide rollers and also engaged by the wiping roller.

8. A starching machine comprising a main frame, a starch tank mounted thereon, a pivoted frame having angle side members each with one web shaped to enter the tank and the other web to then rest on the main frame, a main drum journaled on the pivoted frame in position to enter the tank and having a driving gear exterior to the tank, driving means for the driving gear carried by the main frame and into and out of engagement with which driving means the gear of the main drum is movable with the pivoted frame, a tension roller mounted on the pivoted frame at the end thereof remote from the pivot of the said frame, posts rising from the pivoted frame adjacent the pivoted end, arms extending from the posts in overriding relation to the main drum to points adjacent to the tension roller, another straining

roller carried by the free ends of the arms, an elastically mounted wiping roller carried by the posts in position to engage the main drum at a high point thereof and on the 5 rising side thereof when in operation, guide rollers carried by the pivoted frame both above and below the main drum, and cords or belts extending about the tension rollers, about the guide rollers and also engaged by 10 the wiping roller, the guide rollers below the main drum being provided with depending supports, pivoted arms carried by the supports of one of the last-named guide rollers, pressure rollers carried by the pivoted arms 15 in engagement with the main drum in underdriving relation thereto, and elastic tension means connected to the pivoted arms and to the pivoted frame to hold the pressure rollers in engagement with the main 20 drum.

9. In a starching machine, a starching drum and two series of cords or belts in partial encircling relation to the drum, both cords or belts having coacting runs extend-

ing to the same side of the drum, those runs 25 approaching the drum converging and first meeting at the drum and those runs moving away from the drum diverging.

10. In a starching machine, a starching drum and two series of cords or belts in 30 partial encircling relation to the drum, both cords or belts having coacting runs extending to the same side of the drum, those runs approaching the drum converging and first meeting at the drum and those runs moving 35 away from the drum diverging, and a wiping roller engaging the drum and the cords or belts embracing it at a high point on said drum on the side thereof remote from the converging and diverging runs of the 40 cords or belts.

In testimony, that I claim the foregoing as my own, I have hereto affixed my signature in the presence of two witnesses.

OLOF MILLER.
